UNITED STATES PATENT OFFICE.

WILLIAM J. HEINAUER, OF MASSILLON, OHIO, ASSIGNOR OF ONE-HALF TO FREDERICK J. PARRY, OF MASSILLON, OHIO.

MACHINE FOR POLISHING RODS.

1,243,837.

Specification of Letters Patent. Patented Oct. 23, 1917.

Application filed November 8, 1916. Serial No. 130,234.

To all whom it may concern:

Be it known that I, WILLIAM J. HEINAUER, a citizen of the United States, residing at Massillon, in the county of Stark and 5 State of Ohio, have invented certain new and useful Improvements in Machines for Polishing Rods, of which the following is a specification.

This invention relates to apparatus for 10 polishing bars or rods of circular cross section. One object of the invention is to provide an apparatus by the use of which bars or rods of circular cross section may be rapidly polished without being deformed.

15 Another object of the invention is to provide an apparatus for the stated purpose in which the parts subjected to wear may be readily renewed and also to provide an apparatus in which the members directly engaging the rod or bar to be polished may be 20 readily changed so as to conform to the diameter of the bar or rod.

Other objects of the invention are to provide means whereby the polishing material 25 may be readily fed into chambers provided therefor, and also to provide means whereby the members containing the polishing material will be effectually held to the work. Other incidental objects of the invention 30 will appear as the description of the same proceeds.

The invention is illustrated in the accompanying drawings and will be particularly pointed out in the claims appended hereto.

35 In the drawings:

Figure 1 is a plan view of an apparatus embodying my improvements;

Fig. 2 is an end view of the same;

Fig. 3 is a longitudinal section;

40 Fig. 4 is a detail perspective view of the polishing block.

In carrying out my invention, I employ a cylinder or rotatable member 1 which is equipped at its ends with trunnions 2 adapted 45 to be journaled in suitable bearings, indicated at 3, which may be formed at the upper ends of standards rigidly secured in place or may be otherwise provided in a fixed location. One of the bearings 3 is 50 formed with an extension or lateral bracket 4 having one or more bearings 5 disposed with their axes at a right angle to the axis of the bearing 3, as clearly shown in Figs. 1 and 3. The body or cylinder 1 is equipped 55 at one end with a pulley 6 whereby motion

may be imparted to the body, as will be readily understood, and this pulley 6 may be formed integral with the body or cylinder, as shown, or may be otherwise fixed thereto, as will be readily understood. The 60 body or cylinder 1 is bored axially, as shown at 7, and feed rollers 8 are disposed in the vertical plane of the said bore and above and below the horizontal plane of the same so that a rod or bar placed between the said 65 feed rollers will be directed into the bore and when the rollers are rotated will be fed through the same as will be readily understood. The feed rollers are constructed with

grooved peripheries whereby they may readily engage the rod to be polished and are carried by the shafts which are journaled in and extend through the bearings 5, a gear 9 being secured upon the end of either or both 70 of said shafts and connected with the actuating motor so that the said feed rollers will be positively rotated in the operation of the device. At intervals along the body 1, I construct radial recesses or chambers 10

which open at their inner ends into the bore 7 and have plugs 11 fitted in their outer ends, as shown. Between the chambers 10, bushings 12 are fitted in the bore 7 of the body and these bushings are interchangeable 75 and have external diameters corresponding to the diameter of the bore of the body 1 while their internal diameters are sufficient to cause them to fit closely to the rod to be polished but not small enough to bind on said rod. The bushings, therefore, serve as 80

guides and supports for the rod in its movement through the body and also serve to remove the large rough particles which may be upon the rod when it is received at the polishing apparatus. Between the opposed 85 ends of adjacent bushings, I fit the polishing blocks 13 which may be of hard wood or any other material which will hold the polishing compound to the work. These blocks are provided with grooves 14 in their 90 opposed faces which receive the rod and are also constructed with small openings 15 through which the polishing compound may escape to the work. The polishing blocks are of such length and width that they will 95 fit easily within the respective recesses or chambers 10 of the body and are disposed against the inner faces of receptacles or boxes 16 which carry the oil or polishing material. These boxes are constructed with 100

105

110

openings 17 through their inner walls which register with the openings 15 in the polishing blocks and the outer sides of the boxes are closed by cap plates 18 which are held 5 to the boxes by springs 19 bearing against the boxes and the plugs 11, as shown. A filling tube 20 is inserted centrally through the plug 11 and has its inner end screwed or otherwise rigidly secured in the cap plate 10 18, the springs 19 being coiled around the said filling tube, as clearly shown in Fig. 3. The outer end of the filling tube is closed by a plug 21 and has sufficient clearance in the plug 11 to play freely therein, the spring 19 15 serving to hold the polishing block to the work with a constant tension. By adjusting the plug 11, the tension of the spring 19 may be regulated and the box 16 may be adjusted radially so as to permit the use of 20 the device for polishing a larger or a smaller rod, as may be necessary.

It is thought the operation of the device will be readily understood from the foregoing description, taken in connection with 25 the accompanying drawings. It is obvious that the rod must be held against rotation while it is fed through the body 1 which is rotated at a high speed. The feed rollers 8 will grip the rod with such a degree of 30 firmness that the operator will have no trouble in preventing rotation of the rod as it passes through the rotating body 1. After the end of the rod emerges from the delivery end of the rotating body, it may be grasped 35 by the operator and rotation of the rod then manually prevented without effort. If the feed rollers be omitted and the body 1 secured against rotation, the rod to be polished may be rotated as it is caused to pass through 40 the body and the desired results thus obtained, but I prefer to hold the bar or rod against rotation and rotate the polishing body. The bushings 12 may be readily interchanged so that bushings of proper diameter 45 to accurately accommodate and fit the rod to be polished may be employed. The oil or other polishing material is fed through the tubes 20 into the boxes 16 and from said boxes will escape through the outlets 17 and 50 15 to the work and the rapid rotation of the polishing blocks 13, in conjunction with the flow of the polishing material into the slight space between the blocks and the rod will quickly produce a high polish on the surface 55 of the rod. When the polishing blocks are to be renewed, it is necessary merely to remove the plugs 11 at the outer ends of the proper radial chambers or recesses of the polishing body, whereupon the boxes 16 and 60 the polishing blocks will be withdrawn and new parts may be easily substituted. The boxes which contain the polishing material and the parts which coat therewith are all inclosed in the polishing body so that damage thereto by accidental contact with adja-

cent objects is obviated and the springs which are disposed between the outer plugs and the boxes will hold the polishing blocks to the work with the proper tension under all conditions. The device is exceedingly 70 simple in the construction and arrangement of its parts and will be found highly efficient for the purposes for which it is designed.

Having thus described the invention, what 75 is claimed as new is:

1. An apparatus for the purpose set forth comprising a polishing body having a longitudinal bore to receive a rod to be polished, polishing blocks fitted within the body and 80 projecting within the bore of the same to engage the rod, and means for supplying polishing material to the said blocks.

2. In an apparatus for the purpose set forth, the combination of a polishing body 85 having a longitudinal bore to receive a rod to be polished and radial recesses communicating with said bore, polishing blocks fitted in the inner ends of said recesses to project into the bore and engage the rod to 90 be polished, means for supplying polishing material to said blocks, springs disposed within the recesses and yieldably holding the blocks to the said rod, and means for varying the tension of said springs. 95

3. In an apparatus for the purpose set forth, the combination of a polishing body having a longitudinal bore to receive a rod to be polished, polishing blocks fitted within the body and extending into the bore to engage the rod to be polished, means for supplying polishing material to said blocks and variable pressure devices bearing upon the 100 said blocks to hold them to the rod to be polished. 105

4. An apparatus for the purpose set forth comprising a polishing body having a longitudinal bore to receive a rod to be polished, interchangeable bushings adapted to fit in said bore and around the rod, polishing blocks carried by the body and disposed to engage the rod between opposed ends of adjacent bushings, and means for effecting relative rotation between the polishing body and the rod while causing the rod to move 110 through said bushings. 115

5. In an apparatus for the purpose set forth, the combination of a polishing body having a longitudinal bore and radial recesses communicating with said bore, boxes 120 fitted within the said recesses at the inner ends thereof, means for feeding polishing material to the boxes and means within the outer portions of the recesses for yieldably holding the said boxes toward the bore of 125 the polishing member.

6. In an apparatus for the purpose set forth, the combination of a polishing body having a longitudinal bore and radial recesses communicating with said bore, pol- 130

ishing members at the inner ends of the recesses, means within the recesses to supply polishing material to said members, plugs closing the outer ends of said recesses, and 5 springs bearing against said plugs to yieldably hold the polishing members toward the bore of the polishing body.

7. An apparatus for the purpose set forth comprising a polishing body having a longitudinal bore and radial recesses communicating with the bore, boxes mounted in 10

the inner ends of said recesses, filling tubes secured to and extending outwardly from said boxes, plugs closing the outer ends of said recesses and fitting around the filling 15 tubes, and springs coiled around the tubes between the boxes and the said plugs and bearing against the same to hold the boxes yieldably toward the bore of the polishing body.

In testimony whereof I affix my signature.
WILLIAM J. HEINAUER. [L. S.]
